The ornamental design for an adjustable fixture for aligning column grid array substrates, as shown and described.

DESCRIPTION

FIG. 1 is a top perspective view of an adjustable fixture for aligning column grid array substrates, showing our new design;

FIG. 2 is a bottom perspective view thereof;

FIG. 3 is a top view thereof;

FIG. 4 is a bottom view thereof;

FIG. 5 is a left side view thereof;

FIG. 6 is a right side view thereof;

FIG. 7 is a front view thereof; and,

FIG. 8 is a rear view thereof.

The broken lines in the drawings represent portions of the adjustable fixture for aligning column grid array substrates that form not part of the claimed design.
